UNITED STATES PATENT OFFICE.

GEORGE P. WIGGINTON, OF KALAMAZOO, MICHIGAN, ASSIGNEE TO KALAMAZOO LOOSE LEAF BINDER CO., OF KALAMAZOO, MICHIGAN.

BINDER DEVICE.

1,264,240

Specification of Letters Patent. Patented Apr. 30, 1918.

Application filed November 28, 1915. Serial No. 63,566.

To all whom it may concern:

Be it known that I, George P. WIGGINTON, a citizen of the United States, residing at Kalamazoo, county of Kalamazoo, State of Michigan, have invented certain new and useful Improvements in Binder Devices, of which the following is a specification.

This invention relates to improvements in binder devices.

10 My present improvements are especially designed by me for use with temporary binders or loose sheet holders such as are illustrated and described in Letters Patent No. 1,174,458, issued to me March 7, 1916, 15 and I have shown one form of the binder illustrated in that patent in connection with my present improvements in order to more closely illustrate their manner of use. My present improvements are, however, adapted and desirable for use with various forms of temporary binders having separably associated binder members which may be separated to facilitate the removal of the sheets.

20 25 The main objects of this invention are: First, to provide an improved binder device which facilitates the use of temporary binders or loose sheet holders, particularly when they are used for record or accounting purposes.

Second, to provide an improved binder device which facilitates the handling and manipulation of the sheets of temporary binders or loose sheet holders.

30 35 Third, to provide an improved binder device which facilitates the manipulation and handling of temporary binders or loose sheet holders for the insertion or removal of sheets.

40 45 Further objects, and objects relating to structural details, will definitely appear from the detailed description to follow.

I accomplish the objects of my invention by the devices and means described in the following specification. The invention is clearly defined and pointed out in the claims.

50 A structure which is a preferred embodiment of my invention is clearly illustrated in the accompanying drawing, forming a part of this specification, in which:

Figure I is a side view of a structure embodying the features of my invention with a temporary binder arranged therein 55 in position for use.

Fig. II is a plan view, partially in section, on a line corresponding to the broken line 2-2 of Fig. I, a part of the sheets being shown in offset relation.

Fig. III is a vertical longitudinal section on a line corresponding to line 3-3 of Fig. II.

Fig. IV is a detail vertical longitudinal section on a line corresponding to line 4-4 of Fig. II.

Fig. V is a detail vertical section corresponding to that of Fig. III, showing the holder adjusted to position to receive a binder and with a binder arranged thereon.

Fig. VI is a detail longitudinal vertical section on a line corresponding to line 6-6 of Fig. II, showing the relation of the movable posts in the binder.

Fig. VII is a detail section through the post holder on a line corresponding to line 7-7 of Fig. III.

Fig. VIII is an enlarged detail section on a line corresponding to line 8-8 of Fig. V, showing details of the guide member.

Fig. IX is a detail perspective view of a slightly modified form of my invention, with a binder arranged therein.

Fig. X is a perspective view of the structure shown in Fig. IX, with the binder removed, one of the holder side members being shown in one of its raised positions.

Fig. XI is a perspective view of another modification or embodiment of my improved binder device, the same being formed of metal and lacking the adjusting features of the other embodiments.

Fig. XII is a central vertical longitudinal section of the structure shown in Fig. XI.

In the drawing similar reference characters refer to similar parts throughout the several views, and the sectional views are taken looking in the direction of the little arrows at the ends of the section lines.

Referring to the drawings, the binder illustrated comprises a pair of covers 1 and 2 which are provided with chambers to receive the adjusting mechanism. The binding strips 3 extend between the covers. The adjusting mechanism is preferably that shown in U. S. Letters Patent No. 878,340, Feb. 4, 1908, to Harry F. Bushong, and comprises the screw mechanism 4 in one cover and the ratchet mechanism 5 in the other.

I preferably provide clamping members 6 which are pivotally connected to the covers.

The clamping members 6 have sockets 7 for the removable posts 8. The sheets or leaves 9 are provided with notches 10 adapted to receive the binding strips 3, the notches being open at the rear edge of the sheets, and with holes 11 adapted to receive the posts 8. These holes are closed so that when the posts are engaged therewith the sheets cannot be removed except as they are lifted 10 from the ends of the posts or freed by the removal of the posts. When the posts are removed the sheets are freed from the binder. When the posts are inserted and the clamping members 6 clamped thereon the sheets 15 are securely retained within the binders. The sheets are provided with a plurality of the spaced notches 10 and correspondingly spaced holes, so that, if desired, a portion of the sheets may be arranged in an offset relation, as shown in Fig. II, with registering slots and holes when in either position. This arrangement of parts is substantially that shown in my said Letters Patent above referred to.

25 I provide a pair of holders each adapted to receive one of the binder members comprising, in the structure illustrated, the cover and clamping bar, and support the same so that the sheets may be arranged 30 thereon. These holders, which I designate generally by the numerals 12 and 13, in Fig. I of the drawing, are mounted on a pair of supporting base members 14. The holder 12 comprises a side member 15 and an end member 16, while the holder 13 comprises a side member 17 and an end member 18. The end members are mounted in a relatively fixed relation with their upper edges meeting. The end members have registering 35 slots 45 adapted to receive the binding strips. The side members are mounted on pivots 19 so that they may be swung to coacting relation with the end members of the holders, as shown in Fig. III, for instance, or to a 40 horizontal or an approximately horizontal position, as shown in Fig. V. The side members are adjustably supported on their pivots by the slotted links 20 pivotally connected to the inner ends of the side members 45 at 21 and having teeth 22 adapted to engage the bolts 23. The bolts are provided with clamping nuts for securing the links in their 50 adjusted positions.

With the parts thus arranged, the side 55 members of the holders may be swung to their horizontal position to receive the binder members in arranging the binder in the holder and with the binder members resting thereon swung into position to coact 60 with the end members of the holders and the inner ends of the sheets adjusted against the end members of the holders.

The end members of the holders are preferably arranged so that the end member 16 65 is at right angles to its coacting side mem-

ber 15 when the side member is swung to operative position, thereby assisting in alining the sheets to receive the posts.

The end member 18 is preferably disposed at an acute angle to its coacting side member 17 so that when the sheets are adjusted on the holder their outer ends are supported in a stepped relation to facilitate the fingering of the sheets.

To assist in alining the slots and holes of 75 the sheets I provide the end member 16 with a guide 24 and the end member 18 with a similar guide 25, the notches of the sheets being adapted to be engaged with these guides. The guide 24 is made removable 80 so that it may be removed to permit the adjustment of the binder members in closing the binders. To facilitate this the end member 16 of the holder 12 is slotted at 26 and provided with a pair of slide plates 27 for 85 the slide 28 secured to the guide so that it may be inserted and removed by longitudinal movement.

This guide is also preferably adapted as a gage, being provided with a scale 29 having 90 indicia thereon indicating the proper length of post to be used, that is, the thickness of the sheet body as indicated by the scale indicates the proper length of post.

To further facilitate the selection of posts 95 I mount a holder 30 having a series of pockets 31 for sets of posts of different lengths. This holder is mounted on the back of the holder side member 17 so that the posts project above the upper edge thereof. The 100 pockets are provided with indicia 32 corresponding to the indicia on the guide 24.

With the parts thus arranged the sheets 105 may be readily disposed on one of the binder members, either in an alined body or with part of the sheets offset and they are guided so that the removable posts may be readily inserted and the binding strips swung into the slots. When one binder member is adjusted upon the other the guide 24 is 110 removed so as not to interfere with the alining of the same thereon.

In the modification shown in Figs. IX and X the side members of the holder are 115 hinged at 33 to the end members, the outer ends of the holders being supported by links 20. This embodiment does not have the advantage of side members adjustable to a horizontal position.

In the embodiment shown in Figs. XI and 120 XII the holders 34 and 35 are formed integrally of a piece of metal suitably shaped. These holders are supported by a base comprising bottom member 36 having feet 37 thereon and uprights 38 conformed to fit the 125 side and end members of the holder and riveted to the base, the end members having registering slots 39 adapted to receive the binding strips. The end member of the holder 34 is provided with a removable guide 130

40 having headed studs 41 on its rear side adapted to engage the slots 42. The upper end of the guide is curved to fit over the apex of the end members which is also curved.

5 My improved binder device greatly facilitates the use of temporary binders for the keeping of records, particularly where it is desired to keep such records on typewriting machines. The sheets are supported so that they are all readily accessible and the wear and tear on the sheets in handling is minimized.

10 I have illustrated and described my improvements in a practical embodiment. I have shown certain modifications which I find satisfactory and desirable for certain conditions and uses but have not attempted to illustrate or describe all the modifications 15 which I contemplate as I believe the disclosure made will enable those skilled in the art to which my invention relates to embody or adapt the same as conditions may require. I desire, however, to be understood 20 as claiming my improvements specifically in the form illustrated as well as broadly within the scope of the appended claims.

25 Having thus described my invention, what I claim as new and desire to secure by Letters Patent, is:

30 1. In a binder device, the combination of a pair of base members, a pair of holders each comprising side and end members disposed in an opposed relation with their end members adjacent and oppositely inclined and with the upper edges of said end members meeting, said end members having registering binding strip openings therein, 35 said side members being pivotally mounted at their outer ends on said bases, and notched links for adjustably supporting the inner ends of said side members so that they may be adjusted to and supported in a coacting 40 relation to said end members or to a substantially horizontal position.

45 2. In a binder device, the combination of a pair of holders each comprising side and end members disposed oppositely and with their end member adjacent, said side members being pivotally mounted at their outer ends, means for adjustably supporting the inner ends of said side members so that they may be adjusted to and supported in a coacting 50 relation to said end members or to a substantially horizontal position, aligned guide members on said end members, one of said guide members being removably supported in a slide way so that it may be removed and introduced by a longitudinal movement.

55 3. In a binder device, the combination of a pair of holders each comprising side and end members disposed oppositely and with their end members adjacent, said side mem-

bers being pivotally mounted at their outer ends, and means for adjustably supporting the inner ends of said side member, so that they may be adjusted to and supported in coacting relation to said end members or to a substantially horizontal position.

4. A binder device comprising a pair of 75 holders each having side and end members disposed in an opposed relation with their end members adjacent, said end members having registering openings therein, said side members being adjustably supported so that they may be adjusted to a coacting relation to said end members or to substantially horizontal positions.

5. In a binder device, the combination of 80 a pair of holders each comprising side and end members disposed oppositely and with their end members adjacent, and means for adjustably supporting the said side members so that they may be adjusted to and supported in coacting relation to said end members or to a substantially horizontal position.

6. A binder device comprising a holder 90 having a side member and an end member, means for adjustably supporting said side member so that it may be adjusted to coacting relation with said end member or to a substantially horizontal position, and a 95 guide member removably supported on said end member, said guide member being supported in a slide way so that it may be removed and introduced by longitudinal movement.

7. A binder device comprising a holder 100 having a side member and an end member, means for adjustably supporting said side member so that it may be adjusted to coacting relation with said end member or to a substantially horizontal position, a guide member supported on said end member, said guide member being provided with indicia, and a post holder having pockets with indicia corresponding to the indicia of said 110 guide member.

8. A binder device comprising an end member disposed in an inclined position, and a side member supported to be adjusted to an oppositely inclined coacting relation 115 to said end member to provide a trough-shaped holder or to a substantially horizontal position to support sheets.

9. In a binder device, the combination of 120 a pair of holders comprising side and end members, said holders being disposed oppositely with their end members adjacent, said end members having registering binding strip openings therein, and aligned guide members on said end members disposed between said binding strip openings, one of said guide members being removably supported in a slide way so that it may be removed and introduced by longitudinal movement.

10. In a binder device, the combination of a pair of holders comprising side and end members, said holders being disposed oppositely with their end members adjacent, said end members having registering binding strip openings therein, and alined guide members on said end members disposed between said binding strip openings. 60
11. In a binder device, the combination of a pair of holders comprising side and end members, said holders being disposed oppositely with their end members adjacent, said end members having alined binding strip openings therein, and a guide member with which notched sheets may be engaged to facilitate the alining of the sheets mounted on one end member between the binding strip openings thereof. 65
12. In a binder device, the combination of a pair of holders comprising side and end members, said holders being disposed oppositely with their end members adjacent, and a removable guide member, said guide member being removably supported in a slide way on one of said end members so that it may be removed and introduced by longitudinal movement. 70
13. A binder device comprising a holder having side and end members, and a guide member with which the edges of the sheets arranged in said holder may be engaged, said guide member being removably supported in a slide way on said end member so that it may be removed and introduced by a longitudinal movement without the removal of the sheets. 75
14. A binder device comprising a holder having a side member and an end member, said end member having binding strip openings therein, and a guide member removably mounted on said end member between said openings. 80
15. A binder device comprising a holder having side and end members, and a guide member with which the edges of the sheets arranged on said holder may be engaged, mounted on said end member so as to be removed without removing the sheets. 85
16. A binder device comprising a holder having a side and an end member, a guide member removably mounted on said end member, such guide member being provided with indicia, and a post holder having pockets with indicia corresponding to the indicia of said guide member. 90
17. A binder device comprising a holder having an end member and a side member, said end member being provided with gag- 95 ing indicia for the sheet body, and a post
- holder having pockets with indicia corresponding to said indicia of said holder. 100
18. A binder device comprising a holder adapted to receive a binder member with sheets arranged thereon, said holder being provided with gaging indicia for the sheet body, and a holder for posts of different lengths provided with indicia corresponding to the said indicia of said holder. 105
19. A binder device comprising a holder adapted to receive a binder in open position with sheets arranged therein, said holder being provided with gaging indicia for the sheet body. 110
20. A sheet holder comprising an end member and a side member adapted to support the sheets with their ends abutting said end member, and a guide member mounted on said end member and provided with sheet gaging indicia. 115
21. A binder device, comprising an end member and a side member supported for adjustment relative to said end member so that it may be adjusted to coact therewith and provide a trough-shaped holder or to a substantially horizontal position. 120
22. In a device of the class described, the combination of a pair of end members disposed in a relatively fixed outwardly inclined relation, and a pair of side members mounted so that they may be adjusted to a substantially horizontal position or to an inwardly inclined relation to coact with said end members and provide a pair of trough-like holders. 125
23. In a device of the class described, the combination of a pair of holders each comprising end members and coacting adjustably supported side members adapted to be adjusted to provide substantially horizontal supports or to coact with said end members and provide a pair of trough-shaped holders. 130
24. In a binder device, the combination of holders comprising side and end members disposed oppositely with their end members adjacent, and means for adjustably supporting one side member so that it may be adjusted to and supported in coacting relation to its end member to provide a trough-shaped holder or to a substantially horizontal position. 135

In witness whereof, I have hereunto set my hand and seal in the presence of two witnesses.

GEORGE P. WIGGINTON. [L. S.]
